UNITED STATES PATENT OFFICE.

MAURICE E. HADDEN, OF SAVANNAH, NEW YORK.

DESIGN FOR A PARING-KNIFE.

SPECIFICATION forming part of Design No. 29,378, dated September 20, 1898.

Application filed August 19, 1898. Serial No. 689,020. Term of patent 7 years.

To all whom it may concern:

Be it known that I, MAURICE E. HADDEN, of Savannah, in the county of Wayne and State of New York, have invented and produced a new and original Design for a Paring-Knife, of which the following is a full, clear, and exact specification.

Reference is to be had to the accompanying drawings, forming a part of this specification, in which similar characters of reference indicate corresponding parts in all the figures.

Figure 1 is a perspective view of a paring-knife, showing my design. Fig. 2 is a plan view of the same. Fig. 3 is a side elevation of the same, and Fig. 4 is a transverse section of the same on the line 4-4 in Fig. 3.

The design consists of a handle A, from

which projects the knife-blade B, formed with a double curve or corrugations B' B'', extending the entire length of the blade, with the back B³ curved downward near its outer end to terminate in a point, the curved portion B' being dished or concaved, as plainly indicated in Fig. 4.

The leading feature of my design consists of a knife-blade curved in opposite directions, as at B' B''.

I claim—

The design for a paring-knife, as herein shown and described.

MAURICE E. HADDEN.
